PROGRESSING CAVITY PUMP CONSTRUCTION

John David Bourke and Harry Louis Conrad, Springfield, Ohio, assignors to Robbins & Myers, Inc., Springfield, Ohio, a corporation of Ohio

Application March 31, 1958, Serial No. 725,119

5 Claims. (Cl. 103—117)

This invention relates to a progressing cavity type pump construction and relates particularly to improvements useful in connection with high pressure pumps of different types which are dealing with high abrasive or corrosive materials.

In a pump of the progressing cavity type there is an axial thrust against the pump stator in a direction opposite to the flow of fluid being pumped. This axial thrust becomes an important factor in high pressure pumps.

It is, therefore, one of the objects of the present invention to provide a novel construction whereby the axial thrust on the pump stator is transmitted directly to the pump housing.

Where pumps of this type have been used to pump high abrasive or corrosive fluids for which they are particularly adapted because of the fact that the rotor is generally of stainless steel and the stator of rubber, the casing has been made of high alloys to withstand the corrosive or abrasive action. Actually, however, only certain portions of the casing come into contact with the abrasive or corrosive material and it is, therefore, another object of the present invention to provide an arrangement whereby only those portions of the pump which come into contact with the material being pumped need be made of high alloys.

Another high cost item which enters into the picture in connection with high pressure pumps is the connection of a connecting rod to the pump rotor which will be strong enough to transmit the necessary torque. Rotors for progressing cavity pumps are generally made on a lathe from stainless steel bar stock and in order to provide sufficient stock to transmit torque at the connecting rod a large size of bar stock must be used, but then the greater portion of this is removed in turning the rotor.

It is therefore another object of the present invention to provide a connecting rod connection of sufficient torque transmitting ability which is not wasteful of bar stock for the rotors. The rotor may be made of bar stock which is just sufficiently large to turn the helical convolutions.

These and other objects of the invention which will be pointed out in more detail hereinafter or which will be apparent to one skilled in the art upon reading these specifications, we accomplish by that certain construction and arrangement of parts of which we shall now disclose an exemplary embodiment.

Reference is made to the drawings forming a part hereof and in which:

Figure 1 is a plan view of a typical high pressure progressing cavity pump according to the invention.

Figure 2 is a fragmentary cross-sectional view on an enlarged scale taken on the line 2—2 of Figure 1.

Figure 3 is a cross-sectional view taken on the line 3—3 of Figure 1, also on an enlarged scale; and

Figure 4 is a cross-sectional view through the stator and stator housing showing the relationship of the stator and rotor.

2

Briefly, in the practice of our invention, we provide on the tubular casing within which the stator is mounted, an annular abutment adjacent each end and we provide attachment rings for each end of the tubular casing, each having a cooperating annular abutment. These attachment rings are bolted respectively to the inlet casing portion and to an outlet fitting. In this way thrusts are transmitted by the tubular stator casing to the outlet fitting and to the pump inlet casing. The inlet casing, which serves also for one end of the connecting rod, is secured to a separate casing portion which carries a bearing for the drive shaft and the other end of the connecting rod. The bearing portion of the casing and the inlet portion of the casing are separated and sealed from each other by a sleeve and packing gland. In this way, the portion of the casing having the bearing for the drive shaft need not be made of a high alloy material because it does not come into contact with the material being pumped. Therefore, the inlet casing portion, the outlet fitting, the rotor, the connecting rod and the above mentioned sleeve are the only portions which need to be of high alloy material. The connecting rod connection which is exposed to the fluid being pumped comprises a stainless steel sleeve pinned both to the rotor and to the connecting rod, as will be described in greater detail hereinafter.

Referring now in more detail to the drawings, 10 indicates the outlet fitting; 11 the attachment flange bolted thereto by bolts 12; 13 is the pump stator casing; 14 are 30 a plurality of mounting brackets therefor; 15 is another attachment flange bolted by means of bolts 16 to the inlet and connecting rod casing 17. 18 is the bearing and connecting rod casing which is bolted to the casing 17 by the bolts 19. The drive shaft is indicated at 20.

As best seen in Figure 4, the pump rotor 21 which is generally of stainless steel operates within the stator 22 which is generally of rubber. The principles of the progressing cavity pump are well known and will not be described further herein. The stator 22 is bonded to the stator housing 13. At each end the housing 13 has a groove and a sealing ring 23 seated therein. Inwardly of the sealing ring 23 at each end of the housing 13, there is provided the annular groove or notch 24. The casing 13 is mounted by means of the mounting brackets 14 which do not form a part of the present invention and need not be described further.

At the discharge end of the pump, as best seen in Figure 3, there is provided the attachment ring 11 which may be bolted by means of the bolts 11a to the casing element 13. The attachment ring 11 has the bolting flange 11b by means of which it is bolted to the bolting flange 10b of the outlet fitting 10 by means of the bolts 12. It will be observed that the attachment ring 11 is provided with an annular flange or abutment 11c which engages the annular groove 24 in the casing element 13.

As seen in Figure 2, the attachment ring 15 is provided with the bolting flange 15a and is bolted to the member 17 by the bolts 16. It will also be seen that the member 15 has the annular flange or abutment 15b which engages in the annular groove 24 of the casing 13. Thus, it will be seen that the cooperation between the flange 11c and the annular abutment provided by a wall of the groove 24, and between the flange 15b and the annular abutment provided by a wall of the groove 24 at the other end of the member 13 serve to take up the axial thrust produced against the stator 22 toward the right in the figures, as a result of pumping fluid from right to left.

The section 17 is provided with the inlet 17a and also has the opening 17b and bolting flange 25. By means of bolts 19 the flange 25 is bolted to the casing portion 18 which carries the bearings 26 and 27 for the drive shaft 20. Secured to the drive shaft 20 is the sleeve 28 which

extends through the opening 17b and is sealed thereagainst by the packing gland 29.

In this manner it will be clear that the fluid being pumped and entering at 17a is only in contact with the member 17, the sleeve 28, the connecting rod 30 and the parts within the casing element 17. Therefore the casing element 18 and its associated parts may be made of ordinary cast iron because they will not be affected by the material being pumped.

The connecting rod 30 is secured at one end to the shaft 20 by means of the pin 31. The pin 31 passes through a flared hole 32 in the connecting rod 30 so that the connecting rod 30 may have the necessary degree of freedom with respect to the pin 31. The end of the connecting rod 30 is part-spherical in form and fits within a recess formed at the end of the shaft 20. The pin 31 passes through the hole 32 and through holes in the shaft 20 and is held in place by means of screws 33 passing through collar 34. The end of the rotor has the cylindrical portion 21a which fits rather tightly into a stainless steel sleeve 35. A pin 36 passes through the sleeve 35 and a hole in the portion 21a. To the right of the pin 36 an O-ring 37 or other suitable seal is provided between the rotor and the sleeve 35.

The end of the connecting rod 30 is part-spherical in form as clearly seen in Figure 2 and also has a flared hole 38 through which the pin 39 passes. The pin 39 also passes through aligned holes in the sleeve 35. By virtue of this construction, the connecting rod 30 may have rocking movement universally to a limited degree with respect to the rotor 21. A suitable rubber seal 40 is provided to seal between the connecting rod 30 and the sleeve 35 so that the inner end of the connecting rod 30, the pin 39 and the flared hole 38 are protected from and sealed from the fluid being pumped.

The pins 36 and 39 are held in place by a retaining sleeve 41 which is pressed rather tightly over the sleeve 35 and against abutment 42 on the sleeve 35.

By this construction, the portion 21a of the rotor need not be of sufficient size to receive the connecting rod head and transmit the necessary torque because the sleeve and pin construction gives it the necessary strength and cross-section. In this way a large amount of rotor material is saved. It will also be clear that the fluid being pumped contacts only the interior of the casing element 17, the connecting rod, the sleeve 28, the sleeves 35 and 41, the rotor, the stator, and the outlet fitting 10. The various brackets 14 and the casing element 18 may simply be made of cast iron or other inexpensive material.

It will be understood that various modifications may be made without departing from the spirit of the invention and we therefore do not intend to limit ourselves otherwise than as called for in the claims which follow.

Having now fully described our invention, what we claim as new and desire to secure by Letters Patent is:

1. In a helical gear pump wherein an internally helically threaded resilient stator pumpingly coacts with an externally helically threaded rigid rotor, a rigid tubular casing embracing said stator, said tubular casing having an annular abutment adjacent each end thereof, an outlet fitting and an inlet and connecting rod casing element for said pump, an attachment ring secured to said tubular casing at each end thereof, each said ring having an annular abutment cooperating with the respective annular abutments on said tubular casing, one of said attachment rings being bolted to said outlet fitting and the other attachment ring being bolted to said inlet and connecting rod casing element, a bearing and connecting rod casing element bolted to said inlet and connecting rod casing element and carrying a drive shaft for said pump, a packing gland sleeve secured to said drive shaft and extending into said inlet and connecting rod casing, a packing gland surrounding said packing gland sleeve, a connecting rod connected at one end to said drive shaft and

at its other end to said rotor and passing freely through said packing gland sleeve, said last named connection comprising a metallic sleeve into which the ends of said connecting rod and rotor are fitted, a pin extending through said metallic sleeve and rotor, a pin extending through said metallic sleeve and connecting rod, and a retaining sleeve fitted over said metallic sleeve to retain said pins in place, sealing means between the end of said rotor and said metallic sleeve, sealing means between said connecting rod and the adjacent end of said metallic sleeve, said outlet fitting, rotor, connecting rod, sleeves, and inlet and connecting rod casing element being of a material which is not deleteriously affected by the fluid being pumped.

15 2. In a helical gear pump wherein an internally helically threaded resilient stator pumpingly coacts with an externally helically threaded rigid rotor, a rigid tubular casing embracing said stator, said tubular casing having an annular abutment adjacent each end thereof, an outlet fitting and an inlet and connecting rod casing element for said pump, an attachment ring secured to said tubular casing at each end thereof, each said ring having an annular abutment cooperating with the respective annular abutments on said tubular casing, one of said attachment rings being bolted to said outlet fitting and the other attachment ring being bolted to said inlet and connecting rod casing element.

20 3. In a helical gear pump wherein an internally helically threaded stator pumpingly coacts with an externally helically threaded rigid rotor, and the rotor orbits in a cylindrical path, and wherein a connecting rod transmits rotation from a drive shaft running on its own true axis to said orbiting rotor, a coupling between said connecting rod and rotor comprising a metallic sleeve fitting 25 tightly over the end of said rotor and a pin passing through said sleeve and rotor, said connecting rod having a part-spherical end fitting freely within said sleeve and a pin passing through said sleeve and connecting rod, the pin hole in said connecting rod being flared to permit 30 rocking movement of said connecting rod, sealing means between said connecting rod and the adjacent end of said sleeve, and a retaining sleeve fitting over said metallic sleeve to retain said pins in place.

35 4. In a high pressure helical gear pump wherein an internally helically threaded stator pumpingly coacts with an externally helically threaded rigid rotor, and the rotor orbits in a cylindrical path, and wherein a connecting rod transmits rotation from a drive shaft running on its own true axis to said orbiting rotor, a high torque coupling 40 between said connecting rod and rotor, comprising

45 a metallic sleeve fitted tightly over the end of said rotor and a pin passing through said sleeve and rotor, said pin being of sufficient diameter and length to transmit the requisite torque in shear and compression, and said sleeve being of sufficient thickness to withstand said 50 torque after drilling of a hole for said pin, said connecting rod having a part-spherical end fitting freely within said sleeve and a pin passing through said sleeve and connecting rod, the pin hole in said connecting rod being flared to permit rocking movement of said connecting rod, 55 sealing means between said connecting rod and the adjacent end of said sleeve, and a retaining sleeve fitted over said metallic sleeve to retain said pins in place.

60 5. In a helical gear pump wherein an internally helically threaded stator pumpingly coacts with an externally helically threaded rigid rotor, said pump being useful for pumping materials having a deleterious effect on ordinary metals, a bearing and connecting rod housing member, an inlet and connecting rod housing member bolted to 65 said bearing and connecting rod housing member with communicating bores in alignment, a stator casing member bolted at one end to said inlet and connecting rod housing member, an outlet fitting bolted to the other end of said stator casing member, said stator being disposed 70 in said stator casing member, said rotor being in pumping 75

engagement within said stator and extending into said inlet and connecting rod housing member, a drive shaft having a bearing in said bearing and connecting rod housing member, a sleeve secured to said drive shaft and extending through said aligned bores into said inlet and connecting rod housing member, a packing gland sealing said sleeve with respect to said aligned bores, and a connecting rod connected at one end to said drive shaft in said bearing and connecting rod housing member, passing inside said sleeve into said inlet and connecting rod housing member and connected to said rotor, said inlet and connecting rod housing member, sleeves, connecting rod, connection, rotor, and outlet fitting being of a metal

5 which is not deleteriously affected by the fluid being pumped.
